YORK.

TEST-CIRCUITS.

1,187,928.

Specification of Letters Patent. Patented June 20, 1916.

Application filed March 2, 1915. Serial No. 11,586.

To all whom it may concern:

Be it known that I, FRANK N. REEVES, a citizen of the United States, residing at Newark, in the county of Essex and State 5 of New Jersey, have invented certain new and useful Improvements in Test-Circuits, of which the following is a full, clear, concise, and exact description.

This invention relates to line selection 10 and more particularly to the circuits by means of which a selector switch finds and connects itself to a desired one of a group of lines. The lines may be of any kind whatever, the only requisite being that busy 15 potential be supplied to the test contacts of the undesired lines of a group. In the present embodiment this busy potential will be supplied by connecting the test contacts to ground, although obviously the ground 20 and battery connections of the test circuits may be reversed. The testing circuits herein disclosed have been found especially satisfactory in selecting an idle one from a group of trunks.

One of the objects of the invention is 25 the provision of test circuits for use with switches which hunt in groups, whereby a switch is prevented from causing a line to test busy before it has seized said line, and 30 thus the passing over of the desired line by seeking switches is prevented.

Another object of the invention is the provision of circuits of this character in 35 which the probability of double connections or the connection of a plurality of switches to the same line is reduced to a minimum.

A further object of the invention is the provision of circuits whereby testing may 40 take place with certainty and at high speed.

In the drawings, only so much of the 45 circuits are disclosed as will be useful in obtaining a clear understanding of the test circuits and their operation.

The switch illustrated is of the panel type 50 and may be of a character such as shown in Patent No. 1,123,696, although obviously any other switch of the same general type may be employed, that is, any switch which employs an operating magnet which is continuously energized during the movement 55 of the switch and in which a centering interrupter brush is also provided.

The sequence switch shown in the draw-

ings may be of the structure such as shown 55 in Patent No. 1,127,808.

In the drawings, the numerals which appear adjacent the several sequence switch contacts represent the sequence switch positions in which the respective contacts will be closed, with the exception that the controlling contacts, which appear directly over each of the sequence switches, will be open in the positions represented by the numerals adjacent thereto, and these numerals therefore represent the positions in which 60 the sequence switch may stop.

As the two switches shown in the drawing 65 represent switches of the same group and are therefore identical both in function and operation, the circuits of only the switch 70 at the left will be described in detail, and corresponding parts in the switch and circuits at the right will be indicated by corresponding reference characters primed.

In the drawings, 1 represents a switch 75 shaft to which is secured one or more sets of brushes 2. Fixed to the shaft 1 is an interrupter brush 3 adapted to traverse the conducting segment of an interrupter 4. The brush 3 is arranged to engage a conducting segment at all times except when the brushes of the set 2 are centrally positioned on a set of contacts in the terminal bank 5. Secured to the shaft 1, at the lower 80 end thereof, is an elevating bar 6 adapted to be forced into engagement with the power drum 7 by means of the idler pulley 8, carried by the armature of the clutch or motor magnet 9.

We will now assume that in the process of 90 setting up a call the sequence switches have been advanced in any usual manner to position 6, in which position a circuit will be completed from battery through the right winding of test relay 10, sequence switch 95 contact 11 (6) to ground. Relay 10 is energized and completes a circuit from battery through sequence switch motor magnet 12, contact 13 (6), front contact and armature of relay 10, to ground. The sequence 100 switch thereupon moves from position 6 to position 7. In position 7 a holding circuit is completed for relay 10 through the right winding thereof, sequence switch contact 11 (7), brush 3 and bottom segment of interrupter 4 to ground. In this position a cir-

cuit is also completed from battery, through clutch magnet 9, sequence switch contact 14 (7), front contact and armature of relay 10, to ground. The clutch magnet 9 is energized and through the idler pulley 8 forces the bar 6 into engagement with the rotating friction drum 7, and the brushes of set 2 are moved along the contacts in the bank 5. By any desired means the test contacts of 10 undesired lines will be supplied with ground potential.

We will now assume that the contacts in the bank 5 are connection circuit or trunk contacts, and that the first six trunks in the 15 group are busy and are therefore connected to ground. When the brushes of set 2 are centrally positioned on the first or lowermost set of contacts, the interrupter brush 3 will be positioned on an insulating segment and the circuit through the right winding of relay 10 will be broken. However, at this time a circuit will extend from battery through the left winding of relay 10, its left contact and armature, test brush 20 15 and the contact engaged thereby, to ground, thus insuring that the test relay 10 will remain energized, and hence the circuit of the clutch magnet will remain closed until the interrupter brush 3 again engages a 25 conducting segment of the interrupter 4.

The shaft 1 will continue to move upward, the holding circuit for relay 10 being alternately completed through the test brush 3 and the test contacts of the undesired lines, which under the present assumption are busy trunks, and the interrupter brush 3 and conducting segment of the interrupter 4. When, however, the brushes of set 2 engage the contacts of an idle trunk 40 (which we will assume is the upper one in the drawing), no ground potential will be found on the test contact thereof, and the circuit through the left winding of test relay 10 will be interrupted. The circuit 45 through the right winding, however, will be maintained until the brushes of the set 2 have been centrally positioned on the contacts of the set, when brush 3 will move on an insulating segment of the interrupter 6, breaking the holding circuit through the right winding of the test relay. The armatures of relay 10 will fall off and the left armature will open the holding circuit through the left winding of said relay. 50 The right armature in falling off will open the circuit of the clutch magnet 9, and close at its bank contact a circuit from battery through sequence switch motor magnet 12, contact 16 (7), contact and back armature of relay 10 to ground, whereupon the sequence switch will move to position 8. Busy potential may be supplied to the multiple test contacts of the selected circuit through sequence switch contact 17, and the back contact and left armature of relay 10. 55

In order to make the advantages of this invention more obvious, we will assume that at the time switch 1 centers on the contacts of an idle circuit, the test brush of switch 1' has just engaged a multiple contact of said circuit and the interrupter brush 3' is still in electrical engagement with the grounded interrupter plate 4'. With the present circuits the ground on interrupter brush 3' will not be so associated with the test contact of said circuit as to cause the circuit to test busy to switch 1, as would be the case with similar circuits formerly used. 70 75

What is claimed is:

1. In combination, a line selecting switch, 80 a motor magnet therefor, an interrupter actuated in response to the movement of said switch, a circuit for said magnet, means including a pair of relay windings for controlling said magnet circuit, parallel circuits for said windings, one extending through the test brush of said switch and the other through said interrupter, and means for preventing the reenergization of said motor magnet after the desired line 90 has been found.

2. In combination, a line selecting switch, a motor magnet therefor, an interrupter actuated in response to the movement of said switch, a test relay, a circuit for said magnet controlled by said relay, a pair of windings on said relay, parallel circuits for said windings, one being completed through the test brush of said switch and the other through said interrupter, and means for preventing the reenergization of said motor magnet after the desired line 95 has been found.

3. In combination, a switch, a motor magnet therefor, an interrupter actuated in the movement of said switch, a relay, a circuit for said magnet extending through front contacts of said relay, a pair of windings on said relay, and circuits for said windings, one of said circuits extending 105 through a test brush of said switch and the other through said interrupter.

4. In combination, a switch, a motor magnet therefor, an interrupter actuated in the movement of said switch, a test relay 115 having a pair of energizing windings, a circuit for said motor magnet extending through front contacts of said relay, means for energizing said relay, and holding circuits for said windings, one of said circuits 120 extending through a test brush of said switch and the other through said interrupter.

5. In combination, a switch, a motor magnet therefor, an interrupter actuated in 125 the movement of said switch, a test relay having a pair of energizing windings, a circuit for said motor magnet extending through front contacts of said relay, means for energizing said relay, and holding cir- 130

cuits for said windings alternately completed in the movement of said switch, one of said circuits extending through a test brush of said switch and the other through 5 said interrupter.

6. In combination, a switch, a motor magnet therefor, an interrupter actuated in the movement of said switch, a test relay having a pair of energizing windings, a 10 circuit for said motor magnet extending through front contacts of said relay, means for energizing said relay, and holding circuits for said windings alternately completed in the movement of said switch, one 15 of said circuits extending through a front contact of said relay and a test brush of said switch and the other through said interrupter.

7. In combination, a switch, a motor 20 magnet therefor, an interrupter actuated in the movement of said switch, test contacts of circuits, a test brush for said switch arranged to traverse said contacts a relay having a pair of windings, a circuit for 25 said motor magnet extending through front contacts of said relay, means for energizing said relay, and holding circuits for said relay windings, one being completed 30 through said test brush and the test contacts of busy circuits, and the other through said interrupter.

8. In combination, a switch, a motor 35 magnet therefor, an interrupter actuated in the movement of said switch, test contacts of circuits, a test brush for said switch arranged to traverse said contacts, a relay having a pair of windings, a circuit for 40 said motor magnet extending through front contacts of said relay means for energizing said relay, and holding circuits for said relay windings, one being completed 45 through said test brush and the test contacts of busy circuits, and the other through said interrupter while said brush is passing from the contact of one circuit to the contact of the next.

9. In combination, a switch, a motor 50 magnet therefor, an interrupter actuated in the movement of said switch, a test brush for said switch, test contacts of circuits trav-

ersed by said brush a relay having a pair of windings, a circuit for said motor magnet extending through front contacts of said relay, means for energizing said relay, and holding circuits for said relay windings, one 55 being completed through said test brush and the test contacts of busy circuits, and the other through said interrupter while said brush is passing from the contact of one circuit to the contact of the next. 60

10. In combination, a switch, a motor magnet therefor, an interrupter actuated in the movement of said switch, test contacts of circuits, a test brush for said switch arranged to traverse said contacts, a relay 65 having a pair of windings, a circuit for said motor magnet extending through front contacts of said relay, means for energizing said relay, and holding circuits for said relay windings, one being completed 70 through a contact and armature of said relay, said test brush and the test contacts of busy circuits, and the other through said interrupter while said brush is passing from the contact of one circuit to the contact of 75 the next.

11. In combination, a switch, a motor magnet therefor, an interrupter actuated in the movement of said switch, a test brush for said switch, test contacts of circuits traversed by said brush, a relay having a pair of windings, a circuit for said motor magnet extending through front contacts of 80 said relay, means for energizing said relay, and holding circuits for said relay windings, one being completed through a contact 85 and armature of said relay, said test brush and the test contacts of busy circuits, and the other through said interrupter while 90 said brush is passing from a central position on the contact of one circuit to a corresponding position on the contact of the next circuit.

In witness whereof I hereunto subscribe my name this 26th day of February A. D., 95 1915.

FRANK N. REEVES.
